(57) **CLAIM**

The ornamental design for a handles for manipulating ice tray covers, as shown and described.

DESCRIPTION

FIG. 1 is a front, right side, top perspective view of handles for manipulating ice tray covers showing my new design; FIG. 2 is a rear, right side, bottom perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; and, FIG. 9 is a front, right side, top perspective view thereof showing the top cover portion of an ice tray removed from the bottom portion of the ice tray. The broken lines depict portions of an environment in connection with which the handles for manipulating ice tray covers are used and that form no part of the claimed design.
